UNITED STATES PATENT OFFICE

2,542,033

LIPSTICK CONTAINER

Louis Edward Isele, Oakville, Conn., assignor to
 The Eyelet Specialty Company, Waterbury,
 Conn.

Application March 16, 1948, Serial No. 15,071

1 Claim. (Cl. 206—56)

1

This invention relates to cosmetic holders, and particularly to those employed for containing lipstick materials and other cosmetics or preparations which are generally provided in stick form.

In many devices used for this purpose, the cosmetic material is contained in a carrier or cup which is advanced toward the forward open end of an outer tubular shell, or else is retracted into the shell, the advancing and retracting movements of the cosmetic carrier or cup being effected by the manual rotative movement of a head or disk provided at one end of the outer tubular shell. Very often, inadvertent rotative movement of the impelling device occurs while the holder is contained in the user's handbag, with the result that the cosmetic material is advanced toward the forward end of the holder and into the cap fitted over the same. This often tends to dislodge the cap from the holder, causing the same to fall off the holder within the handbag, thus exposing the cosmetic material to contact with the interior of the bag or with articles contained in the bag. If the pressure of the cosmetic material within the closure cap of the holder is insufficient to dislodge the cap, it is often sufficient to cause the end of the cosmetic material to become misshapen by pressure against the inside of the cap, so that the application of the cosmetic to the lips is inconveniently and unsatisfactorily performed.

It is therefore apparent from the foregoing, that it is desirable to provide a lipstick or other cosmetic container which shall be provided with means acting to prevent advancing or propelling action of the cosmetic-carrying cup while the holder is in a condition of non-use or while it is being carried in a handbag, and the present invention contemplates the provision of such an arrangement. A primary object therefore, is the provision of means by which the elements of the holder which must be relatively moved or rotated to advance the cosmetic-carrying cup, will be held against such movement while the cover or closure cap of the holder is in its closed position. Thus, as long as the cover of the holder is fitted in place while the cosmetic-carrying cup is in its retracted position, the advancement of the cosmetic-carrying cup toward the forward open end of the holder will be prevented. The invention further contemplates the provision of means by which the inner tube of the holder which is normally rotative within the outer shell, shall become locked to the outer shell by the simple placement of the closure cap over the outer shell, so that these elements will thereupon be maintained together as a unit and relative movement of the same prevented, thus preventing operation of the cosmetic-advancing device and preventing the consequent advancement of the cosmetic material out of the holder. With

2

the arrangement set forth, the closure cap, while serving to render the locking means effective to prevent operation of the cosmetic-advancing means, will nevertheless, be freely rotatable on the body of the holder, enabling the holder and its several elements coupled together by the locking device, to be freely rotated as a unit within the cover without causing advancement of the cosmetic material from within the holder.

5 These and other objects are attained by the invention, a more particular description of which will hereinafter be set forth and more particularly pointed out in the claim appended hereto.

10 In the accompanying drawing, wherein an illustrative embodiment of the invention is disclosed:

Fig. 1 is a side elevational view of a cosmetic holder made in accordance with the invention, with the closure cap in a raised position and partly in section;

15 Fig. 2 is a sectional view taken substantially on the line 2—2 of Fig. 1, looking in the direction of the arrows;

20 Fig. 3 is a side elevational view of the outer shell;

25 Fig. 4 is an enlarged view of the lower or base portion of the holder, with parts broken away and other parts in section to show construction;

30 Fig. 5 is a detail view of a portion of one end of the inner tube, showing the formation of the locking tongue out of the same.

35 Referring to the drawing, 1 indicates the outer shell of the holder, the same being of tubular formation, and provided with the forward open end 2 through which the cosmetic stick 6, which may be of lip rouge or other cosmetic material, is advanced to expose the end of the same for

40 application to the lips or face. Fixed within the outer shell 1 is a stationary slotted tube 15, provided with a spiral slot 16. Rotatively mounted within the tube 15 is an inner or propelling tube 3 which, when manually rotated, will advance or retract the cup-shaped cosmetic carrier 5 in the known manner. At one end, the inner or propelling tube 3 is provided with an attached disc-like head 4 located at the rear end of the

45 shell 1 and fixed on the tube 3, said disc-like head constituting a finger-piece for engagement by the fingers to rotate the propelling tube 3 inside of the stationary tube 15 and shell 1. The shell 1 and the propelling tube 3 are held against

50 longitudinal displacement by detents or other known means not shown in detail since the same, and the elements of the structure thus far described are known and in use in the trade. It is sufficient to state that the three tubular elements 1, 15 and 3 are held concentrically, with the inner tube 3 rotative within the stationary tube 15.

55 60

The cosmetic carrier consists of a cup-shaped member 5 in which the stick of cosmetic material is carried, said carrier having a radially extending pin, not shown, which rides in the spiral cam-slot 16 in the wall of the tube 15 and also in a slot provided in the inner or propelling tube 3. This arrangement, which is known in this art, is such that when the head or disk 4 is held between the fingers of one hand and is rotated thereby, the propelling tube 3 will be rotated inside of the shell 1, and the cosmetic carrier 5 will be advanced toward the open end 2 of the shell 1 or else retracted or moved away from said end, according to the direction of rotation of the head 4. It will thus be clear that the advancement or retraction of the cosmetic carrier 5 is dependent upon the rotation of the propelling tube 3 within the shell 1.

To maintain the cosmetic-carrying means against undesirable or inadvertent advancing movement toward the open end 2 of the outer shell 1, a locking device is provided, the same including a resilient tongue 8, struck out of the side of the inner or propelling tube 3, as clearly seen in Fig. 5. It will be noted that the tongue is formed from material forced out of the aperture 14 in the wall of the tube 3 and the base of the tongue arises from the flared end or flange 13 provided on the tube 3. It will be further noted that the tongue 8 has an upper inturned end 18 and is so spaced from the side wall of the tube 3 that the stationary tube 15 and the outer shell 1 will fit between the tongue 8 and the portion of the tube 3 that is located above the flange 13, as seen in Fig. 2.

As noted in Figs. 1 and 3, the outer shell 1 is provided with an aperture or notch 12 extending inwardly from its lower edge, this notch 12 being of a shape and size to receive the tongue 8, and especially the inturned end or tip 18 thereof, when this portion of the tongue is flexed inwardly by pressure imposed upon it by the wall 11 of the closure cap 10, when the closure cap is fitted in place on the container. The closure cap 10 may be of the conventional form used on cosmetic holders, and it includes the skirt portion 11. When the closure cap is telescopically fitted over the outer shell 1 in the known manner, the skirt 11 will ride over the tongue 8 which normally projects out of the aperture or notch 12, as shown in Fig. 2, and forces the free or hooked end 18 of the tongue inwardly, causing said end 18 to enter the notch or aperture 12, as clearly seen in Fig. 4. The notch or aperture 12 is so positioned that it will register with the tongue 8 only when the cosmetic-carrying cup 5 is in its retracted position within the holder. Thus whenever the cup 5 is retracted and the closure cap 10 is placed in its closed or seated position on the holder, the cap will act to thrust the tongue 8 inwardly and will maintain the inturned or hooked end 18 of the same in engagement with the notch or aperture 12 on the outer shell 1. Therefore, while the closure cap remains in position on the holder, a coupling is established between the inner or propelling tube 3 and the outer shell 1 locking these two elements together and preventing any relative movement between the same.

While the closure cap remains in position on the holder, the head 4 can be rotated, inadvertently or otherwise, and when that is done, said head 4, instead of acting to rotate the propelling tube 3 within the shell 1, will rotate the shell 1, tube 75

3 and tube 15 as well as the cup 5 together, or as a unit, within the closure cap 10, and since there will be no relative movement between the tube 3 and the shell 1, the cosmetic-carrying cup 5 will be held against movement relatively to the tube 3 and the cup will not be advanced, but will simply rotate in company with the shell 1 and tubes 3 and 15 within the cap 10. In other words, when the closure cap is in position, a lock is established between the shell 1, tubes 3 and 15 and the carrier 5 which enables these parts to be rotated within the closure cap, but only as a unit and with no relative movement with respect to one another so that the cosmetic carrier is not advanced.

The tongue 8 is so arranged and disposed that the closure cap may be readily slid over it when the closure cap is placed on the holder, and the springy and resilient nature of the tongue 8 is such that the same acts as a friction member tending to hold the cap 10 against inadvertent axial displacement from the holder. At the same time, the arrangement of the tongue is such that it does not prevent rotative movement of the shell 8 behind it when it is not engaged with the notch 12. When engagement between the notch 12 and the tongue 8 is established as heretofore described by the fitment of the closure cap on the holder, tubes 3 and 1 will be coupled together and movement of the cap 5 will be prevented.

As soon as the closure cap is removed, the tongue 8 will spring out to the position of Fig. 2, thus bringing its hooked or inturned end 18 out of the aperture or notch 12 and releasing the coupling between the propelling tube 3 and the outer shell 1 so that the tube 3 can then be rotated within the shell 1 and the cosmetic-carrying cup 5 will then be advanced or retracted in the known manner. When the closure cap is replaced after the cosmetic has been applied and the cup 5 retracted into the holder, the lock between tubes 3 and 1 will be at once established by the entry of the tongue 8 into the notch 12 in the manner described.

Having described one embodiment of the invention, it is obvious that the same is not to be restricted thereto, but is broad enough to cover all structures coming within the scope of the annexed claim.

What I claim is:

In a cosmetic container, an outer tube, a cam-slot tube within the outer tube, a propelling tube within the cam-slot tube, the propelling tube being rotative within the cam-slot tube and outer tube, a cosmetic cup within the propelling tube and having a driving element engaged with said propelling tube and with the cam slot whereby rotative movement of the propelling tube within the cam-slot tube and outer tube will propel or retract the cup, the lower end portion of the propelling tube being flared and having an upstanding spring tongue disposed on the outside of the outer tube, said tongue having its base at the upper part of the flared portion of the propelling tube and having an inturned free end directed upwardly or toward the upper end of the container, the outer tube being provided with a notch in its lower end to receive said tongue, the tongue being normally disposed out of said notch and being forced into the same by a cover member for the container when said cover member is fitted in position over the outer tube.

LOUIS EDWARD ISELE.
